UNITED STATES PATENT OFFICE.

JOHN B. FREYSINGER, OF NEW BRITAIN, CONNECTICUT, ASSIGNOR TO NORTH & JUDD MANUFACTURING COMPANY, OF NEW BRITAIN, CONNECTICUT.

BELT BUCKLE.

Application filed April 24, 1925. Serial No. 25,623.

This invention relates to belt buckles for personal wear and has for its object the provision of a construction whereby the lever or bail may be very easily and cheaply assembled with the gripper so that it cannot be separated therefrom and will operate in a highly efficient manner to rock the gripper and effect release or engagement of the belt. The invention is illustrated in the accompanying drawing and consists in certain novel features which will be hereinafter first fully described and then particularly defined in the claims.

In the drawing:—

15 Figure 1 is a rear elevation of a buckle embodying the present invention;

Figure 2 is a longitudinal section on the line 2—2 of Fig. 1;

20 Figure 3 is a perspective view of the gripper and the lever or bail;

Figure 4 is a section on the line 4—4 of Figure 3.

The face plate 1 may be of the usual or any approved form having side flanges 2 provided at proper points with openings to receive elements whereby the gripper 3 is pivotally mounted upon the rear side of the face plate. The gripper is formed from a single integral blank of sheet metal bent 25 into form in a stamping machine and includes a rear bridging member or head 4, side members or clamping lips 5 and 6, and end members 7. The clamping lips are parallel and their free edges are usually convex, as at 8, to conform to the popular formation of the face plate and effectually clamp the belt thereto, while the end members 7 close the spaces between the ends of the lips and are provided with aligned eccentric openings 9 to receive the pivoting element or elements. The clamping lip 5 is imperforate throughout its area but the lip 6 is provided with aligned notches or open-ended slots 10 at its ends to accommodate 30 the side members of the lever or bail 11. The closed end of this lever or bail constitutes a loop for the engagement of the attaching end of the belt while its side members 12 extend through the slots 10 and have 35 their ends turned outwardly to form trunnions or pivots 13 passing through the openings 9 and the corresponding openings in the flanges 2, the extremities of the trunnions being upset against the outer sides of

the flanges, as indicated at 14, to secure the 55 parts against separation.

The side members of the bail or lever are somewhat resilient so that they may be pressed toward each other, as indicated by dotted lines in Fig. 4, to enter between the 60 end members of the gripper and the slots 10 are long enough to easily admit the bent ends or trunnions of the bail. The slots are also wide enough to allow play of the gripper 65 relative to the bail and the eccentric location of the trunnion or pivot permits the jaw 6 to obtain a strong grip upon the buckled end of the belt when the latter tends to pull in a direction away from the bail.

From the foregoing description, taken in 70 connection with the accompanying drawing, it will be seen that I have provided a very simple, inexpensive and efficient buckle. The gripper presents two clamping lips to engage the belt so that the belt will be very 75 securely held without any detrimental biting into the material of the belt. The pivotal mounting being a part of the bail, the number of parts is minimized and production 80 facilitated while the bail is so engaged with the gripper that the latter may be easily rocked to effect release or engagement of the belt.

Having fully described my invention what I claim as new and desire to secure by Letters-Patent, is:—

1. A belt buckle comprising a body portion including a face plate, a gripper mounted in said body portion and cooperable with said face plate to grip a belt, said gripper 90 having parallel clamping lips, a head connecting the rear edges of the lips, the front edges of the lips constituting belt engaging and clamping elements, and transverse end members forming integral parts of the gripper 95 fitting closely within and supporting the ends of the lips, said end members filling the spaces at the ends of the lips, and means connected with the gripper for operating it.

2. In a belt buckle, the combination of a 100 face plate having side flanges, a gripper including clamping lips and end members between the lips, and a lever bail having its side portions passing through one of the clamping lips and its ends forming trunnions pivotally engaged in the end members of the gripper and the flanges of the face plate.

3. In a belt-buckle, the combination of a face plate, a gripper for cooperation with the face plate and having parallel clamping lips and end members between the lips, and a lever bail engaged in one lip of the gripper whereby to carry and rock the same, said lever bail being pivotally connected with the face plate at the ends of the gripper.
4. In a belt buckle, the combination of a face plate having side flanges, a gripper disposed between the flanges and including clamping lips and end members between the lips and provided in its ends with eccentric openings and in one lip with slots, and a lever bail having its side members passing through said slots and its ends extending outwardly through the openings in the end members of the gripper and pivotally secured in the side flanges of the face plate.

In testimony whereof, I have signed this 20
specification.

JOHN B. FREYSINGER.
